(57) **CLAIM**

The ornamental design for a terminal for smart card, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front elevational view of a first embodiment of terminal for smart card showing my new design;

FIG. 2 is a front elevational view of a second embodiment of terminal for smart card showing my new design;

FIG. 3 is a front elevational view of a third embodiment of terminal for smart card showing my new design;

FIG. 4 is a front elevational view of a fourth embodiment of terminal for smart card showing my new design;

FIG. 5 is a front elevational view of a fifth embodiment of terminal for smart card showing my new design;

FIG. 6 is a front elevational view of a sixth embodiment of terminal for smart card showing my new design;

FIG. 7 is a front elevational view of a seventh embodiment of terminal for smart card showing my new design;

FIG. 8 is a front elevational view of an eighth embodiment of terminal for smart card showing my new design;

FIG. 9 is a front elevational view of a ninth embodiment of terminal for smart card showing my new design;

FIG. 10 is a front elevational view of a tenth embodiment of terminal for smart card showing my new design; and,

FIG. 11 is a front elevational view of an eleventh embodiment of terminal for smart card showing my new design.
